US0D1062181S

(12) United States Design Patent (10) Patent No.: US D1,062,181 S
(45) Date of Patent:  Feb. 18, 2025

(54) SHOE SOLE

(71) Applicant: Canhui Ding, Jinjiang (CN)

(72) Inventor: Canhui Ding, Jinjiang (CN)

() Term: 15 Years

(21) Appl. No.: 29/875,929

(22) Filed: May 12, 2023

(30) Foreign Application Priority Data

Mar. 21, 2023 (CN) 202330137128.2

(51) LOC (15) Cl. 02-04

(52) U.S. Cl.

USPC D2/977; D2/954
